UNITED STATES PATENT OFFICE.

JOHN NORTH, OF MIDDLETOWN, CONNECTICUT.

LIFT OR FORCE PUMP.

SPECIFICATION forming part of Letters Patent No. 380,509, dated April 3, 1888.

Application filed June 9, 1887. Serial No. 240,761. (No model.)

To all whom it may concern:

Be it known that I, JOHN NORTH, a citizen of the United States, residing at Middletown, in the county of Middlesex and State of Connecticut, have invented new and useful Improvements in Lift or Force Pumps, of which the following is a specification.

My invention relates to that class of hand-pumps in which the water is lifted or forced from a lower to a higher level, in contradistinction to those in which a partial vacuum is created by the reciprocation of the plunger and the water raised by the weight of the atmosphere.

It is the purpose of my present invention to provide a simple, durable, and easily-operated mechanism in which liability to freeze, as well as oxidation of the metal, is wholly avoided, while the action of the pump will effect a constant circulation of air, by which the water is purified and the effects of long stagnation prevented.

It is also my purpose to provide a pump of such construction that it may be operated with comparatively little power and quickly produce a plentiful supply of water.

It is one purpose of my invention also to so organize the pump that it will draw water from a well or cistern directly, or when located at a distance therefrom and connected by a suitable pipe entering at or near the bottom of the reservoir.

The invention consists in the several novel features of construction and new combinations of parts hereinafter fully set forth, and definitely pointed out in the claims which follow this specification.

In the accompanying drawings, Figure 1 is a central vertical section of a pump embodying my invention. Fig. 2 is a vertical section in the line 2 2, Fig. 2^a. Fig. 2^a is a partial horizontal section of Fig. 2 in the line 2^a 2^a, Fig. 2. Fig. 3 is a view, partly in section and partly in elevation, showing a modified construction. Fig. 4 is a detail view of the plunger in Fig. 3.

In the said drawings, the reference-numeral 1 designates the body or cylinder of the pump, which may be double, as in Figs. 1, 2, and 2^a, or single, as in Figs. 3 and 4, the construction of the cylinders not being essentially different in either case. It consists of a ver-

tical cylindrical shell of suitable diameter to accommodate the plunger and provided with inlet-ports 2, cut through its wall at a point 55 not far from midway the length of the cylinder. In the inner face of the cylinder are cut circular channels 3, leading from its upper end down to the level of the ports 2, said channels alternating in arrangement with the said ports. 60

The cylinder 1 is part of a base, 4, having an extension, 5, within which is formed a valve-chamber, 6, communicating with the lower end of the cylinder by a water-way, 7. Within the chamber 6 is placed a check-valve, 8, engaging with a seat, 9. A delivery-pipe, 10, is screwed upon a threaded nipple, 11, within which the valve seat 9 is formed. The pipe 10 extends to the point where the water is delivered. 70

Within the cylinder 1 is arranged the plunger 12, composed of an iron bell-shaped shell without packing, to the upper closed end of which the actuating-rod 13 is centrally attached. This plunger operates within the 75 pump-cylinder, and has a close surface-contact below the horizontal plane of the inlet-ports 2. Above this point the plunger bears upon the cheeks 14 of the cylinder-shell, air ingress being given by the air-pipe 15. In order to perfect the work of the plunger, an air-pipe, 15, is tapped into the extension 5, communicating with the water-way 7, between the cylinder 1 and the check-valve 8. The end of this pipe rises above the level of the water in the reservoir, and in a small valve-chamber just beneath the end of said pipe is seated an air-valve, 15^a, which closes as the plunger descends. The pump thus organized is placed 80 in the well, cistern, or other reservoir, upon 90 the bottom thereof, and the actuating-rod, as well as the outlet-pipe, is extended to the surface, or to any point or points where the operation of the pump and the delivery of the water may be desired. The total submersion 95 of the parts prevents oxidation of the iron, and also avoids the freezing which so often disables chain-pumps and occasions the injury of the rubber valves by the repeated use of hot water. 100

The same invention, essentially, may be embodied in a double-acting pump, as shown in the drawings. In this construction two cylinders 1 are mounted upon a prolonged base,

4^a, each cylinder having the construction already set forth. In each of these cylinders a piston or plunger, 12, reciprocates; but instead of the connection with the actuating-rod 5 13 each plunger is provided with a vertical rack-bar, 16, with which is geared a double sector-gear, 17, centrally mounted, relatively to the rack-bars 16, upon a bracket, 18.

The actuating-rod 13 is connected by a pivot-joint, 19, to one of these rack-bars, and its other end is mounted upon a wrist-pin, 20, carried by a gear, 21, journaled on a stud, 22, in a housing, 23, of any suitable pattern. Meshing with the gear 21 is a pinion, 24, also journaled within the housing and driven by the crank 25. In this modified construction the extension 5 is broadened and contains two check-valves, 8, having alternate action, each closing and opening the double water-way 7. 20 In this form, also, an air-pipe, 15, is employed, communicating with the common water-way 7 between the two cylinders and the two check-valves. In order to harmonize the admission of air by this pipe with the alternate action 25 of the cylinders, plungers, and valves, I extend from the bottom of each cylinder an air-chamber, 25^a, which communicates with one of the valve-chambers containing the air-valve 15^a. These air-valves alternate in action with the check-valves 8 and the latter hold the water in the outlet-pipe, while the former permit the rise of the plungers alternately.

I have shown in the drawings nuts 26, which limit the rise of the check-valves 8, as well as 35 air-valve check-nuts 27; but it will readily be understood that any other construction which will effect like results will be within the limits of my invention.

Each plunger 12 is provided with an air-chamber, 12^a, by which the shock of a sudden stroke is softened and all the benefit of an air-globe substantially obtained.

Having thus described my invention, what I claim is—

45 1. In a pump, the combination, with a to-

tally-submerged vertical cylinder having lateral inlet-ports intermediate its ends, of a water-way and a valve-chamber communicating directly with the base of said cylinder, a delivery-pipe rising from said valve-chamber, 50 a check-valve located in said chamber, an air-pipe communicating with said water-way, and a bell-shaped plunger reciprocating in the submerged cylinder to open and close the lateral inlet-ports and force the water admitted through said ports below the plunger through the water-way at the base of the cylinder, and thence through the valve-chamber and delivery-pipe, substantially as described.

2. In a pump, the combination, with a pair 60 of totally-submerged vertical cylinders having lateral inlet-ports, a common delivery-pipe, and alternately-reciprocating plungers, of water-ways leading from the base of each cylinder to a common delivery-pipe, check-valves 65 located between said water-ways and delivery-pipe, an air-pipe communicating with a chamber common to said water-ways, and air-valves located in said chamber, substantially as described.

3. In a pump, the combination of a totally-submerged vertical cylinder mounted upon a base, 4, provided with an extension, 5, having formed therein a water-way, 7, leading from the lower end of the cylinder, and a valve-chamber, 6, and air-chamber 25^a, communicating with said water-way, said vertical cylinder being provided with lateral inlet-ports, 2, vertical channels 3, and check-pieces 14, a bell-shaped plunger, 12, a delivery-pipe, 10, 75 communicating with the base of the cylinder, an air-pipe, 15, check-valve 8, and air-valve 15^a, substantially as described.

In testimony whereof I affix my signature in presence of two witnesses.

JOHN NORTH.
